DESIGN FOR A LACE

William Roger Adaire, Washington, R. I., assignor to Gehring, Solomon & Birnbaum, Inc., New York, N. Y., a corporation of New York

Application February 28, 1935, Serial No. 55,657

Term of patent 3½ years

To all whom it may concern:

Be it known that I, William Roger Adaire, a citizen of the United States, residing at Washington, in the county of Kent and State of Rhode Island, have invented a new, original, and ornamental Design for a Lace, of which the following is a specification, reference being had to the accompanying drawing, forming a part thereof.

The single figure in the drawing is a plan view

of a lace, showing between the dot and dash lines, one repeat of the design which is repeated at regular intervals, the beginning and ending of similar repeats being shown lightly outside the dot and dash lines.

I claim:

The ornamental design for a lace as shown and described.

WILLIAM ROGER ADAIRE.
